(57) CLAIM

The ornamental design for a split sole shoe, as shown and described.

DESCRIPTION

FIG. 1 is a front perspective view of an ornamental design for a split sole shoe according to the present invention;

FIG. 2 is a first side view thereof;

FIG. 3 is a second view thereof;

FIG. 4 is a top view thereof;

FIG. 5 is a bottom view thereof;

FIG. 6 is a front view thereof; and,

FIG. 7 is a back view thereof.

The broken lines on the rear of the shoe in FIGS. 1-4 and 6-7 indicate an unclaimed portion of the split sole shoe.

1 Claim, 6 Drawing Sheets

FIG. 1

FIG. 2

FIG. 3

FIG. 4

FIG. 5

FIG. 6

FIG. 7
